UNITED STATES PATENT OFFICE.

WALTER EDWARD A. REITINGER, OF PAOLA, KANSAS, ASSIGNOR OF ONE-HALF TO
JACOB ERTLE, OF PAOLA, KANSAS.

TOBACCO PIPE.

Application filed January 15, 1925. Serial No. 2,650.

To all whom it may concern:

Be it known that I, WALTER EDWARD A. REITINGER, a citizen of the United States, residing at Paola, in the county of Miami 5 and State of Kansas, have invented a new and useful Tobacco Pipe, of which the following is a specification.

My invention relates to tobacco pipes, and the object of the invention is to provide an 10 inexpensive and sanitary tobacco pipe having facilities for burning tobacco and furnishing cool dry smoke therefrom.

I attain this object and other advantages by means of the structure and parts illustrated in the accompanying drawing in which—

Figure 1, is a vertical section of a tobacco pipe which embodies my invention.

Figure 2, is a plan view of the lower side 20 of the cap member, a part of my invention.

Figure 3, is a cross section through the bowl of the pipe, on the line 3—3, in Figure 1.

Figure 4, is a vertical section of a modified form of the bowl of the pipe, and showing the bowl removable from the pipe bowl and,

Figure 5, is a plan view of the lower end of the pipe bowl.

Similar numerals of reference refer to corresponding parts throughout the several views.

Referring to the drawings—the numeral 1, designates the bowl of the pipe, 2, designates the tobacco bowl for burning the tobacco and 3, is the pipe stem. The pipe bowl may be made of any suitable material or substance, preferably, made of briar wood, because, of its well known durability 40 and beauty. The stem may, also, be made of any suitable material and may be integral with the pipe bowl, or detachably mounted thereon. The pipe bowl, in this instance, is formed cylindrical and, in the 45 lower end of the same, at the vertical axis thereof, is a concentric outlet opening 4, thus forming, between the opening and the inner end of the tobacco bowl, a partition 5, in which are a plurality of holes 6, apertured in vertical direction and providing communication between the tobacco bowl and atmosphere. An annular channel or 50 chamber 7, is formed in the vertical wall of the pipe bowl, the depth of the chamber being substantially the same as the depth of

the tobacco bowl. In the upper portion of the wall of the tobacco bowl are a plurality of horizontally apertured holes 8, thus providing communication between the tobacco bowl and the chamber 7. A cap member 9, 60 is removably mounted on the upper end of the pipe bowl and provided with an annular flange 10, adapted for entering the upper end of the chamber 7, with suitable friction to, thereby, prevent air from entering the chamber, except through the tobacco bowl, and provided with a boss or plug 11, adapted for entering the mouth of the tobacco bowl with suitable friction to, thereby, prevent air from entering the tobacco bowl, except, through the holes at the lower end of the bowl. Intermediate of the length of the pipe bowl, the wall of the bowl is reinforced and through the reinforced portion, 70 is a hole 12, suitable for the reception of the pipe stem, the hole being in communication with the chamber 7. In the modified form of tobacco pipe, shown in Figure 4, the tobacco bowl 2 has at its ends and circumferentially of the bowl laterally projecting flanges 14, which, in operative position, function to seal the chamber 7, thus doing away with the necessity for the flange 10.

To use the tobacco pipe—the cap 9, is removed and the tobacco bowl 2, is loaded with a charge of tobacco, whereupon the cap is again placed on the pipe bowl, the flange 10, thereon being fitted into the upper end of the chamber 7, and the plug 11 fitted into the mouth of the tobacco bowl, thus effectually preventing air from entering the bowl or chamber, at the upper end of the pipe bowl. Then, the smoker takes the pipe stem into his mouth, applies the flame of a lighted match to the lower side of the partition 95 5 and, then drawing or sucking on the stem, in the well known manner of tobacco smoking, draws the flame and air through the holes 6, into the tobacco bowl and ignites the tobacco in the pipe. When the tobacco 100 is burning, the smoke therefrom is drawn by the smoker through the tobacco to the upper end of the tobacco bowl, to and against the lower side of the cap 9, the latter being relatively cooler the smoke is perceptably cooled. From the upper end of the tobacco bowl the smoke is drawn through the holes 8, into the chamber 7, and therefrom, through the pipe stem to the 105 smoker's mouth. After the smoker has 110

made a draught on the pipe, there remains an opening in the bottom thereof, an inner 5 in the chamber 7, and in the upper end of the tobacco bowl a residue of tobacco smoke and which is cooled by contact with the cool cap and the cool outer wall of the chamber, thereby, depositing nicotine and other deleterious substances carried by the smoke, on the wall of the chamber, in the cooling process. Thereafter, the intermittent draughts of the smoker, a smooth, cool, and sanitary tobacco smoke is drawn 10 from the chamber. As the tobacco burns, the ashes are wasted through the holes 6, a gentle tapping or shaking of the pipe will serve to clear the fire of ashes. The bowl and the chamber may be readily 15 and easily cleaned by removing the cap member and brushing or washing out the same.

Having described my invention what I claim is—

In a tobacco pipe, an outer bowl having

an opening in the bottom thereof, an inner bowl removably mounted in said outer bowl and having a plurality of openings in the bottom thereof communicating with atmosphere and provided circumferentially with laterally projecting annular flanges forming with the vertical walls of said inner and outer bowls a chamber, a cap member removably mounted on said bowls and having a plug adapted for sealing the mouth of the inner bowl, a plurality of openings in the vertical wall of the inner bowl and communicating with the chamber surrounding said inner bowl, and a hollow stem piercing the wall of said outer bowl and communicating with the chamber surrounding said inner bowl.

WALTER EDWARD A. REITINGER.
